COUNTERBALANCE

Howard J. Burnish, Sewickley, Pa., assignor, by
mesne assignments, to The National Supply
Company of Delaware, Toledo, Ohio, a cor-
poration of Delaware

Application July 5, 1933, Serial No. 679,026

9 Claims. (Cl. 74—591)

My invention relates more particularly to counterbalances for crank shafts applicable to counterbalancing varying heavy loads to which well drilling and pumping apparatus are subjected.

5 The main object of my invention is to provide a counterbalance applicable to crank shafts which may be required to operate at comparatively high uniform speeds or comparatively low speeds having a pulsating shock to counterbalance. One 10 feature of my invention is the means employed in adjusting counterweights without the requirement of hard manual labor or heavy cumbersome tools.

Another object of my invention is to provide 15 means to definitely adjust to and hold counterweights at the static, the maximum kinetic or intermediate kinetic balanced positions with vernier precision of adjustment.

Another object of my invention is the provision 20 of new and more secure means for attaching counterweights to the perimeter of a crank member.

Another object of my invention is to provide a 25 means for changing the moments or inertia effects of the counterweights, creating a balanced condition between the load and the source of power without removing the weights from the crank element.

A further object is to provide a counterweight 30 and crank structure that is simple in design, economical to manufacture and durable in character.

Other objects will appear from the following description.

In the accompanying drawings I have illustrated 35 two practical embodiments of the principles of my invention, and the embodiment second described is preferable as for commercial use.

Referring to the accompanying drawings, Fig. 1 is a side elevation of one embodiment of the 40 principles of my invention showing the crank arm, the eccentric disk and the counterweights mounted on the latter.

Fig. 2 is a sectional view taken along the irregular line 2—2 in Fig. 1.

45 Fig. 3 is a development of a cross sectional view taken along the arcuate line 3—3 in Fig. 1.

Fig. 4 is a side elevation showing another embodiment of the principles of my invention.

Fig. 5 is a sectional view of the same taken 50 along the line 5—5 in Fig. 4.

Fig. 6 is a broken and enlarged section taken along the line 6—6 in Fig. 4.

Fig. 7 is an enlarged perspective of one of the washers used in connection with the clamping 55 bolts.

Referring first to Figs. 1 to 3 inclusive, 10 represents the crank shaft normally rotated by a suitable source of power, not shown. 11 represents a combined crank arm and disk member which is mounted on and rendered rigid relative to the shaft 10 as by key 12. The element 11 is preferably an integral casting comprising the crank arm 13 disposed radially of the shaft and the circular disk 14 disposed eccentrically of the shaft. The crank arm 13 is given a greater thickness than the body of the disk 14, as clearly illustrated in Fig. 2, the thinner web 16 of the disk, indicated by dotted lines in Fig. 2, being braced by the diametrically disposed rib 21 disposed along the center line 22 of the disk and at right angles to the crank arm.

Adjacent the peripheral edge of the disk and on each side thereof there is formed an annular groove 18, thus providing the disk with an annular T-shaped peripheral edge portion 19. The outer edge of the disk is provided with a plurality of transversely disposed semi-circular slots 20 equally spaced around the circumference of the disk, forming a gear-like perimeter. The numeral 23 indicates the axis of rotation of the disk and crank, which is also the center of rotation of the shaft 10, which center lies in the axis 24 which is at right angles with the axis of the crank 13.

Thus the disk provides a maximum moment arm from the center of rotation 23 to the point of the periphery of the disk most distant from the shaft and a minimum arm from the center 23 to a point on the opposite side of the periphery of the disk. It is thus evident that all the corresponding intermediate positions along both sides of the periphery of the disk between the maximum and the minimum moment arm of the disk constitute equal moment arms of varying lengths. Therefore equal weights placed at corresponding 40 positions about the periphery of the disk will set up a balanced kinetic condition with respect to the center of rotation of the disk.

26 represents arcuate weights formed of two duplicate and complementary parts 27 and 28, 45 each part having a body portion 29 and an inner end portion 30, which end portion is provided with an arcuate recess or groove 31 formed on its inner face to receive one side of the T-shaped periphery 19 of the disk, as shown in Fig. 2, the inturned flanges 32 of the weight parts engaging the neck of the T and thus the parts 27 and 28 clasp the peripheral portion of the disk between them. The weight parts 27 and 28 are clamped together by the bolts 33 which extend through 55

registering holes in the body portions 29 of the weight parts. The inner portions 30 of the weight parts are provided with a series of transverse holes 34 whose centers are disposed along the 5 peripheral edge of the disk when the weights parts are assembled thereon.

The spacing between the consecutive holes 34 in the weight parts differs from the spacing between the consecutive slots 20 in the edge of the 10 disk, and the spacing of the bolt holes and the slots is so related that only a limited number of the holes 34 will register with slots 20 so that the bolts 35 may be inserted through said holes and engage said slots at each position of the 15 weights when they are secured to the disk. Thus in the drawings the bolt holes are shown spaced farther apart than are the slots and the bolts may be inserted in every fifth hole 34 in the 20 weights and every sixth slot 20 in the disk, each weight being thus secured to the disk by two bolts.

The particular spaced relation shown may be varied, as the same was selected to demonstrate an important characteristic of my invention. I 25 have illustrated a certain minimum unit of arcuate distance through which the weight may be adjusted but obviously by changing the spaced relation of the holes in the weights and the 30 slots in the disks the minimum unit of arcuate distance may be varied.

It is evident that the described vernier arrangement of weights may be adjusted and positioned with respect to each other and with respect to the disk with an accuracy whose precision is determined by the manufacturing 35 tolerance of the device.

When the weights are placed in the dotted position shown at 26' in Fig. 1 they balance the weight of the crank arm and of the eccentric 40 disk and the device then functions as a flywheel and may be rotated at high speed.

Again, this arrangement of the weights is employed when the pitman has been detached from the crank pin positioned in one of the holes 15 45 as when hoisting or withdrawing tools from a well.

When the pitman is attached to a wrist pin positioned in one of the holes 15 and the loads on the pitman are pulsating the weights are adjusted in opposite direction about the periphery of the disk to selected positions of equal moment arms which balance the pulsating shocks and eliminate vibration.

The eccentrically positioned disk provides a 55 means for arranging or positioning the counterweights therearound whereby the mass of one of the weights may have an equal or balanced moment arm with respect to the other weight or they may be so positioned about the periphery of the disk so as to produce moment arms of varied lengths. This feature provides an arrangement that enables the pulsating load that is to be compensated for to be accurately balanced by means of two individually adjusted 60 weights in combination with the crank arm. When the pulsating load to be balanced precedes the pitman in time and the counterweight required to balance this load is less than that 65 available, one of the counterweights may be placed adjacent to the longitudinal axis of the crank arm so that its moment arm in relation thereto is very small, while the other weight may be positioned 90° ahead of the crank arm, at which position it would have a maximum 70 moment arm. The resultant load of the bal-

ancing weights would then precede the pitman and the crank arm in proportion to the respective masses in the moment arms of the counterweights. With this structure the load to be compensated may lead or lag the pitman in time for a considerable number of degrees and still be compensated by the two counterweights of a fixed and determinable mass needing no provision for increasing or decreasing their actual weight, which provision must necessarily be 10 made on other counterbalanced structures to accomplish the same results.

On the other hand if my disk were concentrically mounted on the shaft 10 the counterweights could not produce a condition of a static 15 balance of the mechanism as previously described.

The bolts 33 function to clamp the weight parts together in rigid relation, whereas the bolts 35 perform a dual function, assisting to 20 clamp the weight parts together but also maintaining the weights in the positions to which they have been adjusted about the periphery of the disk. The bolts 35 are subjected to shear strain between the weights and the disk, but 25 should they be sheared off the flanges 32 will continue to hold the weights on the wheel, preventing them from being thrown from the wheel by centrifugal force which might result in serious 30 damage.

To position the counterweights about the wheel elements the bolts 35 are removed and the disk is slowly rotated while the weights remain suspended at the lower portion of the disk, and when the disk and a weight are at the desired relation, the bolts 35 are replaced and tightened to fix the weight in its selected position. This feature of my invention eliminates the use of heavy tools and hard manual labor in placing the weights in 35 their proper position and it is both novel and 40 highly advantageous.

Referring now to Figs. 4 to 7 inclusive wherein I have illustrated the preferred embodiment of the principles of my invention, 36 represents the combined crank arm and disk and an integral 45 casting which is eccentrically mounted on and keyed, as at 12, to the shaft 10. Said casting comprises a relatively thickened fan-like portion 37, the heavier crank arm portion 38 being disposed 50 radially of the axis of movement of the disk and provided with the pin holes 15, the relatively thin webs 39 which may be provided with apertures 40 and the heavier perimetral edge portion which is grooved at either side as at 18 to form the T-shaped peripheral edge 19 as in the first described 55 embodiment. The weights 41 are composed of the complementary parts or halves 42 and 43. The inner faces of the weight parts are recessed 60 at their inner ends to fit over the edge portion of the disk 36, as more clearly illustrated in Figs. 5 and 6, and said parts are provided with registering socket holes 44 in which are fixed the pins 45 which extend inwardly into the grooves 18 of the disk and have rotatably mounted thereon the annular rollers 46, antifriction bearings 47 65 being preferably interposed between the pins and the rollers.

When in place the weight parts are rigidly clamped together and to the disk by means of bolts 48 extending through registering holes 49 70 in the weight parts adjacent to the edge of the disk.

The outer ends of the holes 49 are countersunk or enlarged to form non-circular seats, and 75 50 are non-round washers mounted on the head-ends 75

of the bolts 48 and fitting in said seats, said washers having squared outer openings to receive the heads of the bolts 48 to prevent their turning.

5 The weight parts are also held together by means of pins 51 extending through registering holes in the weight parts and having their ends provided with washers 52 and cotter pins 53 occupying the countersunk ends of said holes.

10 Two sets of rollers for each pair of counter-weight parts are usually sufficient and I prefer to provide three spaced apart clamping bolts.

If desired the rollers may be omitted from the pins and shoes substituted.

15 When the weights are to be adjusted the clamping bolts are loosened so that the weights will depend from the lower portion of the disk and the disk is then rotated until it attains its proper relation to one of the weights.

20 The clamping bolts are then tightened rigidly securing the weight to the disk and the disk is then rotated until it attains its desired relation with the second weight which is then clamped rigidly to the disk. When the disks are in their 25 freely suspended condition the disk turns relative to the weights with great ease.

It is obvious that with the last described movement of the principles of my invention great accuracy and nicety of adjustment is obtained in 30 positioning the weights relative to the disk.

I claim:—

1. In counterbalance mechanism for use in connection with a rotary crank shaft, the combination of a circular disk arranged to be mounted 35 on the shaft and provided with a peripheral rim of substantially T-shape cross-section, a two-part weight mounted on the disk, said weight-parts having complementary faces which mate in surface contact in a plane normal to the axis of the 40 disk and which faces are recessed to provide arcuate surfaces to mate with the convex peripheral edge of the disk, and said weight-parts having inwardly extending portions to engage the sides of the rim of the disk, rollers carried by the in- 45 wardly extending portions and engaging the inner arcuate surfaces of the rim of the disk, and clamping bolts disposed substantially parallel with the axis of the disk and engaging registering holes in the weight-parts to hold the weight- 50 parts together and on the disk in such a manner as to be wholly supported from the rim of the disk.

2. In a counterbalance device for well pumping apparatus, the combination with a rotary 55 crank shaft, of a circular disk eccentrically mounted on the crank shaft, a weight, means for pendulously supporting said weight from the periphery of said disk, said weight being freely slideable relative to the disk when the latter is 60 rotated, and means for clamping said weight to said disk.

3. In a counterbalance device for well pumping apparatus, the combination with a rotary crank shaft, of a circular disk eccentrically 65 mounted on the shaft, a plurality of counterweights, means for pendulously supporting said weights from the periphery of said disk, said weights being freely slideable relative to the disk when the latter is rotated, and means for clamp- 70 ing said weights to said disk.

4. In a counterbalance device for well pumping apparatus, the combination with a rotary crank shaft, of a circular disk eccentrically mounted on the crank shaft, a weight, means 75 for pendulously supporting said weight from the

periphery of said disk, said weight being freely slideable relative to the disk when the latter is rotated, and whereby the said weight may be circumferentially adjusted at any position on the periphery of said disk, the said means including 5 instrumentalities whereby the said disk may be rotated through any predetermined degree while said weight is pendulously supported therefrom, and means for clamping said weight to said disk.

5. In a counterbalance device for well pumping apparatus, the combination with a rotary crank shaft, of a circular disk eccentrically mounted on the crank shaft, a plurality of counterweights, means for pendulously supporting said 10 weights from the periphery of said disk, said weights being freely slideable relative to the disk when the latter is rotated, and means whereby the said weights may be circumferentially adjusted at any position on the periphery of said disk, the same means including instrumentalities 15 whereby the said disk may be rotated through any predetermined degree while said weights are pendulously supported therefrom and one or both of said weights clamped to said disk, and whereby the said disk may be further rotated and another 20 of said weights is clamped thereto.

6. In a counterbalance device for well pumping apparatus, the combination with a rotary crank shaft, of a circular disk mounted on the crank shaft and provided with a peripheral rim 30 of substantially T-shape cross section, a two-part counterweight, each part having a portion for engagement with one of the inner arcuate surfaces of the rim of the disk whereby said weight may be wholly and pendulously and slideably supported from said disk during relative rotation of the same, and means for clamping said weight parts to the disk.

7. In a counterbalance device for well pumping apparatus, the combination with a rotary crank shaft, of a circular disk mounted on the crank shaft and provided with a peripheral rim of substantially T-shape cross section, a two-part counterweight, each part having a portion for engagement with one of the inner arcuate surfaces of the rim of the disk whereby said weight may be wholly and pendulously and slideably supported from said disk during relative rotation of the same and means for clamping the weight parts together and to the disk.

8. In a counterbalance device for well pumping apparatus, the combination with a rotary crank shaft, of a circular disk mounted on the crank shaft and provided with a peripheral rim of substantially T-shape cross section, a plurality 55 of two-part weights, each weight part being complementary and having a portion for engagement with one of the inner arcuate surfaces of the rim of the disk whereby said weights may be wholly and pendulously and slideably supported from said T-shape rim during relative rotation of the same, and means whereby the said weights may be circumferentially adjusted at any position on the periphery of said disk, the said means comprising instrumentalities whereby the said disk 60 may be rotated through any predetermined degree while said weights are pendulously supported therefrom and one or both of said weights clamped to said disk, and whereby the said disk may be further rotated and another of said 65 weights is clamped thereto.

9. In a counterbalance device for well pumping apparatus, the combination with a rotary crank shaft, of a circular disk mounted on the crank shaft and provided with a peripheral rim 75

of substantially T-shape cross section, a two-part counterweight, each part having a portion for engagement with one of the inner arcuate surfaces of the rim of the disk whereby said weight may be wholly and pendulously and slidably supported from said T-shape rim during relative rotation of the same, the outer surface of said

rim being provided with transverse recesses, and bolts extending through aligned holes in the weight parts and engaging selected recesses to prevent relative rotation between the disk and the weight.

HOWARD J. BURNISH.
